YARNICK and C. M. YARNICK. Assignors of U. S. Patent.

Patented April 26, 1853.

DES 559

John B. Smith, of Philadelphia, Pa.

Assignor to

C. W. Warnick & F. Leibrandt, of Philadelphia aforesaid.

Letters Patent No. 559 - Dated Apr. 26th 1853.

num

The schedule referred to in these Letters Patent and making part of the same

numnumnum

To all whom it may concern:

Be it known that I, John B. Smith, of the city and County of Philadelphia, and State of Pennsylvania, have invented or produced a new and original design in the cook stove called the

"Portable Range"

and I do hereby declare that the following is a full, clear and exact description of the same; reference being had to the annexed drawings forming part of this specification, which represents an elevation of the front plate, foot, and oven door of the stove.

The front plate B, is surrounded by a rim formed of a succession of beads a, except at that portion of the plate occupied by the ash hole covering B, which is a plain concave with the apertures C, which are capable of being covered by a slide in the usual manner. Directly over the ash hole door is the square d, enclosed by the bead s, having within it an ornament in bas-relief, consisting of a flower e, in the centre, with leaves f, issuing from it laterally, and branches h, running towards the corners of the square, the whole being arranged and having the configuration shown in the drawing.

To the right of the square d, is the oven door A, raised above the surface of the plate B, by the mouldings k, arranged as shown in the drawing and bearing on its panel an ornament in bas-relief consisting of a flower l, with branches m, and leaves n, issuing from it, combined with the lozenge figures p, the whole having the configuration shown by the drawings.

Between the door A, and the edge of the plate B, and surrounded by the bead f, is the ornament q, in bas-relief representing a vase containing a plant bearing clusters of fruit, the several parts arranged as seen

160

Des. 559

in the drawing.

Upon the plate B, above the door A, is the inscription "Warnick & Leibrandt Philadelphia," in raised capitals, and below the door the inscription "Portable Range 1853," in raised capitals and numerals.

The foot C, has the curved shape shown in the drawings, and is ornamented in relief by the flower f, foliage g, sweeps x, and scrolls w, together with the lines u, and v, between the ornamental portions, the whole being arranged as shown in the drawings.

What I claim as my invention or production and desire to secure by Letters Patent, is

The configuration and arrangement of the ornaments and mouldings upon the plate B, door A, and foot C, as set forth in this specification and accompanying drawings, forming a new and original design for the front of a portable range.

In testimony whereof, I have hereunto signed my name before two subscribing witnesses.
